UNITED STATES PATENT OFFICE.

ANTHONY ZISK, OF BALTIMORE, MARYLAND.

DESIGN FOR A COMBINED SCHOLAR'S COMPANION AND PUZZLE.

53,391.

Specification for Design.

Patented May 27, 1919.

Application filed February 26, 1919. Serial No. 279,445. Term of patent 7 years.

To all whom it may concern:

Be it known that I, ANTHONY ZISK, a citizen of Russia, residing at Baltimore, in the State of Maryland, have invented a new, original, and ornamental Design for a Combined Scholar's Companion and Puzzle, of which the following is a specification, reference being had to the accompanying drawing, forming part thereof.

The figure is a perspective view of my new design.

I claim:

The ornamental design for a combined scholar's companion and puzzle, as shown.

ANTHONY ZISK.

Witnesses:

FRANK WUJCK,
JAMES ZISK.
